UNITED STATES PATENT OFFICE.

HENRY S. HALE, OF PHILADELPHIA, PENNSYLVANIA.

SEAT.

SPECIFICATION forming part of Letters Patent No. 271,062, dated January 23, 1883.

Application filed July 28, 1882. (Model.)

To all whom it may concern:

Be it known that I, HENRY S. HALE, a citizen of the United States, residing at Philadelphia, in the county of Philadelphia and State of Pennsylvania, have invented certain new and useful Improvements in Seats, of which the following is a specification, reference being had therein to the accompanying drawings.

10 Figure 1 is a central vertical section of a seat constructed with my improvements. Fig. 2 is a front view of the back, the upholstering being removed. Fig. 3 is a vertical section on the line $x x$ of Fig. 2. Fig. 4 is a horizontal section on the line $y y$ of Fig. 2. Fig. 5 is a rear view of the back. Fig. 6 is a front view of a modified form of seat-back, the upholstering being removed. Fig. 7 is a vertical section on the line $x' x'$ of Fig. 6. Fig. 8 is a horizontal section on the line $y' y'$ of Fig. 6. Fig. 9 is a perspective of a portion of the frame used in constructing a seat-bottom.

In Figs. 2, 4, and 5 of the drawings, A represents one end piece of the back-frame; A', the opposite end piece; B, the top, and B' the bottom. It will be seen that the end pieces, A and A', are curved or otherwise shaped so as to have the central part project outwardly, and in the construction shown in said figures 30 the faces $a a$, which lie toward the upholstering, are inclined toward the center of the seat-back longitudinally, for purposes to be hereinafter set forth. In the construction shown in said figures the top and bottom pieces, B and B', are curved or otherwise shaped so as to have the central part, b, of each project in the direction of the upholstering, the ends b' b' of each of said pieces being bent or projected forward in a similar manner—that is to say, each top and 40 bottom piece has a central curve in one direction and two opposite curves, b²—one between each end and said central part.

C represents a back piece for supporting a row of springs, it being secured to the top and bottom pieces at substantially the central points thereof. It is curved so as to conform substantially to the curve in the end pieces, A A'. Between this central piece, C, and the end pieces, A A', there may be other vertical 50 back pieces, of a number suitable for the purpose required.

Against the face of the center back piece,

C, there are secured coiled springs D, the larger ends or parts of the springs being fastened to the back piece, with an interposed cord, d, and the smaller ends projecting toward the upholstering. The intermediate back pieces (when employed) and the end bars are also each provided with a series of coiled springs arranged in a manner substantially similar to that just described. Over the top of the springs of each series there is arranged a metal spring-band, E, secured to each of the springs in the series by rivets, to be hereinafter specified. The end series of springs—that is, those supported by the end pieces, A A', of the seat—may have the tops joined by a band of woven or fibrous fabric, E', if desired, instead of a metal spring-band, as above described, such a band of fibrous material being advantageous for some reasons at the ends, as will more fully hereinafter appear.

By having the end pieces, A A', and the intermediate back pieces, C, curved, as shown, so as to conform with the outer curved surface of the upholstering of the seat, I avoid the necessity heretofore experienced of employing springs of various sizes, it being possible by thus constructing and arranging the back pieces to use springs D all of the same height.

A wearing-surface over the springs—that is, between them and the upholstering—is provided, as follows:

F F represent metal spring-bands running transversely to the series of springs across the tops of the corresponding springs in the several series. Each of these spring-bands carries a section of the wearing-surface, which consists of a series of wooden slats, G G, secured to the metal spring-band F, each slat lying transversely to the band. Preferably the wooden slats are contiguous to each other, extending in a continuous series from side to side of the seat-back. The wooden slats are connected with the spring-band in such manner as to prevent any displacement of them either longitudinally or laterally. Preferably this connection is effected by means of a strip, H, of woven or fibrous fabric—such as canvas—which is by preference glued to the series of slats G. Before securing the metal bands F to the tops of the series of springs each is fastened to its portion of the wearing-surface—that is, its corresponding series of wooden slats

G and strip of fabric H. These last said parts are united by means of rivets K passing through the metal band F the fabric H, and two or more of the wooden slats G. After being joined to this extent the wearing-surface thus produced is fastened to the tops of a cross-row of springs by means of rivets J and washers or plates J', the washers lying under the upper ends of the coiled springs, and the rivets 5 extending from the under side of said washers through the spring-bands E, (or flexible bands E,) the transverse spring-bands F, the webbing H, and two or more of the slats G. The bands H H, of webbing, are at their ends tacked or 10 otherwise fastened to the end pieces, A A', of the spring-frame. The portions *ii* of the webbing allow an inward and outward movement of the wooden wearing-surface, and at the same time hold the ends in proper position and 15 prevent them from displacement.

If the strips of fabric or webbing E' E' are used over the end series of springs, instead of metal spring-bands E, they (said strips of fabric or webbing) can be utilized to assist in 20 properly steadyng the ends of the wooden wearing-surface and holding them in proper position, while at the same time allowing them sufficient flexibility.

After the several sections of the wearing-surface have been attached to the springs and the spring-frame in the manner above described, a peculiar conformation is given to the wearing-surface as a whole by means of bands L L, running up and down across the several sections. These bands may be made of metal or other suitable material, though I prefer to employ strips of strong fabric or webbing, as by means of them the desired conformation of the surface can be readily produced, sufficient flexibility is provided, and the ends can be readily secured to the top and bottom pieces, B B'. If desired, buckles or other adjusting devices may be situated at L' for the purpose of taking up any slack that may occur while 45 the seat is in use. These bands L are drawn sufficiently taut to draw inward somewhat the several sections of the wearing-surface on vertical lines corresponding substantially with the curves *b* *b* in the top and bottom pieces 50 of the seat-frame. The shape imparted to each section of the wearing-surface is clearly shown by the sectional view in Fig. 4. When the parts are thus arranged it will be seen that there are produced two recesses extending up and down the back of the seat, whereby the seat is made to conform to the backs of two persons. By inclining the faces *a* *a*' of the end pieces of the frame so that they shall be turned somewhat toward the center of the 55 seat, the series of springs carried by said end pieces are so turned or situated as to have the pressure from the backs of the persons leaning against the seat-back bear against the end series of springs on the longitudinal lines of 60 the springs, so that there is an easier yielding of the springs, and there is less danger of

twisting or displacing the latter. The outer ends of the wooden wearing-surfaces tend to swing inwardly somewhat, and this is compensated by bringing the upper ends of the 70 springs at the ends of the frame inward, as shown.

It will be seen that the covering for the back is curved to conform to the shape of the end pieces, A A', and the intermediate back 75 pieces, C, of the spring-sections. By using forwardly-curved pieces of this sort for the back of the spring-frame I have succeeded in making available much more room immediately behind the seat than has been attainable with 80 seat-backs as heretofore constructed. This is a matter of great advantage in car-seats, as it gives a greater space between the seats than has been heretofore common.

The seat-back may be mounted at the ends 85 upon any of the ordinary devices for permitting a reversing of the seat.

By having the wearing-surface for the springs made in different sections I can provide the required shape to properly receive 90 the upholstering. The lengths of the wooden slats G may be varied so as to make the different sections narrower or wider, according as it may be desired to bring them closer together.

In Figs. 6, 7, and 8 I have shown a form of 95 seat-back in which use is made of my improved curved back pieces and correspondingly-curved end pieces. In this case the top and bottom pieces are not curved in the manner shown in the other figures. The springs are secured to 100 the said back pieces in the same way as that already described, and the several series are joined together by means of cross-strips F, either of webbing or metal, said strips being riveted to the metal spring-bands E in the 105 way already described. In this construction the sections of the wearing-surface do not extend across the seat-back, but run up and down, the parts *ii* of the strips of webbing H being fastened to the top piece and bottom piece of 110 the spring-frame. The end pieces, A A', in this case do not carry springs, as in the construction above described, the relations of the parts being such as to provide a comfortable seat-back without mounting the end springs thereon. 115

By arranging the sections of the wearing-surface vertically much of the effect can be attained which is produced by the vertical strips L in the other construction—that is to say, a yielding of the back at one end independently 120 of the other—the sections in the construction shown in Figs. 6, 7, and 8 being so related that one will move in or out without materially affecting the adjacent ones.

The seat-sections are permanently fastened 125 in place, and are permanently fastened to the lower canvas, M, of the upholstering by means of rivets *m* *m* or by gluing, so that the spring-sections cannot be removed without first removing the canvas bottom of the upholstering. 130 This permanent fastening is assisted by the cross-bands F, of metal or webbing.

The seat-bottom (or seat proper) is constructed in a manner substantially similar to that above described for making the back, as will be readily seen by again examining Fig. 1.

5 In making the bottom part I arrange the frame A A' B B' so that it can be detachably supported upon the stationary frame C² C³; and in order to throw the upwardly-curved supporting-bars C farther away from the 10 upholstering, to allow the use of longer springs, I employ comparatively broad bars B³, secured to the pieces B B' of the spring-frame. Preferably I provide the connection between the parts B and B³ and B' and B³ by means of offset sets B², extending upwardly from the parts B B'. In order to have the frame light, the parts B and B' are produced by rabbeting a bar of wood, to the under side of which the part B³ is secured. This part B³ not only operates to 15 throw the curved spring-support C down farther, but also serves to provide a fastening for the removable frame when in place on the stationary frame, they (said parts B³) fitting snugly between the end rails of said stationary 20 frame.

I do not in this case claim any invention except those specifically recited in the claims, preferring to claim all other patentable features shown or described in another application, which I have filed as a division hereof.

What I claim is—

1. In a seat, a spring-section consisting of a supporting piece or bar curved at its center toward the upholstering, and a series of springs supported thereon, substantially as set forth.

2. In a seat, a spring-section having a supporting piece or bar curved at the center toward the upholstering, a series of springs of uniform height secured thereto, and devices for joining 40 together the ends of the springs, substantially as set forth.

3. In a seat, a spring-section arranged to provide a rounded or curved wearing-surface next to the upholstering, it having a supporting piece or bar curved at its center toward the upholstering, a series of coiled springs supported thereon, and a strip of webbing or fabric, H, running over the tops of the springs and secured at the ends to the spring-frame, 45 substantially as set forth.

4. In a seat, a spring-section arranged to provide a rounded or curved wearing-surface next to the upholstering, it having a supporting piece or bar curved at its center toward the upholstering, in combination with a series 55 of coiled springs of uniform height, attached to said piece or bar, a metal spring-band extending over the tops of said springs, and a strip, H, of webbing or fabric, secured at its ends to the spring-frame, and at points between its ends to the metal spring-band and to the coiled springs, and arranged to hold the top of the spring-section in place, substantially as set forth.

5. In a seat, a spring-section arranged to provide a curved or rounded wearing-surface

next to the upholstering, it having a supporting piece or bar curved at its center toward the upholstering, in combination with a series of coiled springs of uniform height, and a flexible wearing-surface consisting of a series of thin wooden slats extending across the series of springs, and fastening devices for securing said series of slats to the springs and to the curved supporting piece or bar, substantially 75 as set forth.

6. In a seat, a spring-section having a supporting piece or bar, a series of springs attached thereto, a wearing-surface or fabric consisting of a series of wooden slats, each arranged transversely to the series of coiled springs, and means for flexibly securing said series of wooden slats to the coiled springs, in combination with a canvas or covering-piece, M, secured to the spring-frame, and means for permanently 85 securing said canvas or covering-piece to the outer surface of the wooden slats, substantially as set forth.

7. In a seat-back, the combination, with the spring-frame having end pieces curved at their 90 centers toward the upholstering, of two or more spring-sections, each composed of a back supporting piece or bar curved at the center toward the upholstering, with a series of coiled springs of uniform height secured thereto, and 95 a flexible wearing-surface secured to the outer ends of the springs, whereby a rounded or curved surface is provided for the upholstering, and whereby, also, there is produced an enlargement of room in rear of the seat-back, 100 substantially as set forth.

8. In a seat-back, the combination of a spring-frame, spring-sections, each having a series of coiled springs arranged vertically in said frame, a flexible wearing-surface secured to the outer 10 end of the springs, and strips or bands L, arranged on lines between the series of springs to compress the wearing-surface, whereby a portion of the seat-back is curved in horizontal cross-section when in place, substantially as 110 set forth.

9. The combination, with the spring-frame having end pieces or bars curved at their centers toward the upholstering, and the intermediate supporting piece or bar, C, curved in a 115 similar manner, the series of coiled springs upon the end bars, respectively, the series of coiled springs supported upon the intermediate bar, the sections of flexible wearing-surface, situated transversely of the bars which 120 support the series of springs, and the strips or bands L, arranged respectively between the intermediate series of springs and the end series, and arranged to compress the wearing-surface, whereby two recesses are formed in the 125 wearing-surface, said recesses having curved lines in horizontal cross-section when the back is in place, substantially as set forth.

10. The combination, with the back supporting pieces or bars, the coiled springs attached thereto in series, the metallic spring-bands F, secured to the tops of the springs on lines 130

transverse to the vertical series, the sections of wearing-surface, each section consisting of a series of wooden slats situated transversely to the metallic spring-bands F, means for securing the wooden slats of each series to its corresponding metal spring-band, and the strips or bands L, arranged to bear against the outer face of said wooden slats to compress the sections of the wearing-surfaces, substantially as and for the purposes set forth.

11. In a seat-back, two or more rows of springs extending horizontally across the seat-back, and sections of wearing-surface, each consisting of a series of wooden slats, and means for 15 flexibly securing said series of wooden slats to a row of springs, the wooden slats of the differ-

ent sections being situated in different planes, whereby a rounded conformation can be provided for the wearing-surface, substantially as set forth.

12. In a seat-back having two recesses curvilinear in horizontal cross-section, the combination, with the upholstering, of a supporting-bar, C, between the said recesses, and a series of coiled springs between said bar and the upholstering, substantially as set forth.

In testimony whereof I affix my signature in presence of two witnesses.

HENRY S. HALE.
